UNITED STATES PATENT OFFICE.

EDWARD PELTZ OFF, OF PHILADELPHIA, PENNSYLVANIA, ASSIGNOR TO THE DENTISTS' SUPPLY COMPANY, OF NEW YORK, N. Y., A CORPORATION OF NEW YORK.

ARTIFICIAL TOOTH AND METHOD OF MAKING THE SAME.

1,348,041.

Specification of Letters Patent. Patented July 27, 1920.

Application filed July 25, 1918. Serial No. 246,681.

To all whom it may concern:

Be it known that I, EDWARD PELTZ OFF, a citizen of the United States, and resident of Philadelphia, county of Philadelphia, and

5 State of Pennsylvania, have invented an Improvement in Artificial Teeth and Method of Making Same, of which the following is a specification.

My invention has for its object the construction of an artificial tooth provided with a pin, said pin either soldered within an anchor which is mechanically applied to the tooth proper or directly applied to the tooth proper after vitrification and in which the 10 attachment of the anchor or the pin is accomplished by flanging the inner end thereof by pressure upon a curved and more or less conical bottom at the base of the hole within the back of the tooth, and thereby 15 causing the flange to be forced into an annular undercut portion or groove at the base of said hole.

More particularly, my object is to enable the attachment of the anchor or pin mechanically to the tooth socket after vitrification or burning, whereby the anchor and pin may be made of a metal having a lower melting temperature than the vitrifying temperature required to convert the bisque 20 of the tooth into porcelain. As a result of this, I am enabled to use anchors and pins of gold or suitable alloys, in place of platinum, which latter has heretofore been largely employed for anchors and pins secured in the bisque at time of vitrification, and I may thus insure a saving of approximately 75 per cent. or more of the cost for 25 the metal for these parts.

In certain forms of my invention the 30 anchors are mechanically attached to the vitrified tooth in the manner hereinafter described and the pin soldered thereto as a secondary operation; in other forms the inner end of the pin itself may be shaped 35 to be mechanically attached to the vitrified tooth; the mode of attachment being similar in both cases.

In general, the mode of mechanical attachment of the anchor or pin consists in 40 providing an inner annular edge which when forced into the hole of the tooth, spreads outwardly into a flaring rim which fits into an undercut groove in the bottom of the hole in the tooth, the extreme bot-

tom of the hole being shaped in a more 55 or less conical form to act as a die to spread the flange when the anchor or pin is forced inward.

My invention consists in the improved tooth structure and the method of making the same as defined in the claims; and my invention will be better understood by reference to the drawings, in which:

Figure 1 is a sectional view through an artificial tooth embodying my invention; 60 Fig. 2 is a perspective view of the anchor tube before being applied to the tooth; Fig. 3 is a perspective view of the anchor or bushing showing the shape assumed after being forced into the hole in the tooth; Fig. 70 4 is a sectional view showing the method of applying the anchor in the hole of the tooth; Fig. 5 is a sectional view illustrating the manner of molding a bisque tooth suitable for my invention; Fig. 6 is a sectional view illustrating my invention in 75 which the pin is directly attached to the tooth; and Fig. 7 is a sectional view showing my invention as applied to a pin of composite form.

2 is the vitrified or porcelain tooth and is provided with a hole 3 in its back portion, the bottom of the hole having a raised hump 4 of a more or less conical form and the base of the hole having a lateral 80 undercut groove 5, the bottom of which slopes upward into the side walls of the conical hump 4. The general shape of the tooth may otherwise be made as desired to suit the particular use of the tooth, the invention being applicable to anterior and posterior teeth of all descriptions, such as 85 vulcanite facings and crowns.

When the porcelain tooth has been molded and vitrified, the anchor and pin may be 90 attached, the former mechanically and the latter by soldering. In molding the bisque tooth preliminary to burning the core for shaping the hole 3 may be made of any suitable material which will burn or fuse 95 100 and thereby be removed at time of vitrifying, a method which is well understood in the art of molding.

A suitable manner of molding the bisque is illustrated in Fig. 5. 10 and 11 are the 105 two parts of the mold, 2^a is the tooth space. A metal post 13 is loosely supported in the hole 12 in part 10 of the mold and its upper

end 14 is shouldered and supports a celluloid or other fusible or combustible core 15 having an annular flange 16 and an upper depressed portion 17 of conical shape. The bisque is molded about the pin 13 and core 15; and after removal and drying the pin 13 is removed and the bisque tooth vitrified by burning. This act burns out the core 15 and leaves the hole as indicated in Figs. 1 and 4.

The tubular anchor 6^a (Fig. 2) is next inserted in the hole 3 of the tooth and, by means of a plunger tool 18 (Fig. 4) having an extension 19 entering the anchor and an annular shoulder which presses upon the outer edge of the anchor, the anchor is forced downward into the hole. The result of this is that the lower part of the anchor is spread by the conical bottom 4 of the hole as indicated in Fig. 4 and ultimately caused to substantially fill the annular undercut groove 5 by being crowded thereinto, as shown at 7 in Fig. 1. In this manner the anchor is mechanically introduced and attached in the tooth. The tool 18 is then withdrawn. The pin 8 may now be soldered in position in the usual manner, the solder being indicated at 9 in Fig. 1. In attaching the pin a small piece of solder is first introduced into the anchor 6 and the pin placed in the hole and anchor upon the solder. By subjecting the tooth to a temperature sufficient to melt the solder the pin becomes firmly soldered in position and solder runs down about the conical part 4 of the tooth and stiffens that portion of the anchor which is flared at the bottom.

Where the separate anchor is to be omitted and the pin is to be directly anchored in the tooth, the construction may be as shown in Figs. 6 and 7. In the particular construction shown in Fig. 6 the lower end of the pin 8^a is bored out to provide an annular end. This, when driven down is flared outward as in the case of the anchor or bushing and the annular flange 7^a tightly fits the groove 5 of the tooth. In Fig. 7, the pin is of a composite character, being made of a thin tube 8^b of metal (corresponding to an elongated anchor) which is attached in place just as the anchor is attached; the pin may then be filled with solder 8^c and fitted with a head 8^d having a shank fitting down into the tubular body and soldered in place. It is evident that this shank of the head may extend sufficiently downward to give additional strength, if so desired.

The anchor may be of any metal to which the pin may be soldered, but gold is preferable because unaffected by the acids of the mouth. The anchor may be made as a thin

tube, continuous circumferentially or of a strip coiled upon a mandrel into tubular form, as is commonly done in making platinum anchors, such details being immaterial to my invention.

I have described my improved method and means in that particularity which I deem to be the best exposition of my invention, and that which I prefer in commercial practice, but I do not restrict or confine myself to the minor or secondary details as such variations, within the scope of the claims, may be resorted to as matters of mechanical skill and without a departure from the spirit of the invention.

Having now described my invention what I claim as new and desire to secure by Letters Patent, is:

1. An artificial tooth having a vitrified body provided with a hole having at the bottom a lateral curved undercut groove, combined with a metal anchor mechanically fitting the hole and attached in the bottom of the hole by having its lower end curved laterally and crowded into the undercut groove to substantially fill the same.

2. In an artificial tooth, a vitrified body having a hole whose bottom is provided with a substantially conical center surrounded with an undercut annular groove.

3. In an artificial tooth, a vitrified body having a hole whose bottom is provided with a substantially conical center surrounded with an undercut annular groove, combined with a metal attaching part having its inner end of tubular form mechanically crowded outwardly into the undercut annular groove of the tooth.

4. In an artificial tooth, a vitrified body having a hole whose bottom is curved from the center outwardly to provide a lateral undercut groove, combined with an attaching structure of metal the inner end of which is annular and curved outward and mechanically crowded against the curved bottom and into the undercut groove.

5. The method of making an artificial tooth which consists of molding a bisque tooth with a hole having a substantially conical bottom and annular undercut groove portion, vitrifying the same, and thereafter mechanically securing a metal attaching part in the hole by forcing the said metal part down upon the conical bottom of the hole and causing thereby an annular lower end of the metal attaching part to be flared laterally and crowded into the undercut groove to make a tight fit therein.

In testimony of which invention, I hereunto set my hand.

EDWARD PELTZ OFF.
